WILLIAM H. McGAULEY, OF PATERSON, NEW JERSEY.

MEANS FOR LUBRICATING SLEEVE-BEARINGS.

No. 886,625.

Specification of Letters Patent.

Patented May 5, 1908.

Application filed September 16, 1907. Serial No. 393,150.

To all whom it may concern:

Be it known that I, WILLIAM H. McGAULEY, a citizen of the United States, residing in Paterson, Passaic county, New Jersey, have invented certain new and useful Improvements in Means for Lubricating Sleeve-Bearings; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My invention relates to means for oiling the sleeve or cylindrical bearings of the spindles of spinning machines or other similar devices.

With reference particularly to spinning spindles, my invention has for its objects to confine the oil against being scattered about after it passes down through and leaves the sleeve bearing and to return it to the top of the bearing to be used over again each time it passes through the bearing. This object being accomplished, it will be obvious that a saving will follow as a matter of course, not only in the lubricating oil and in the labor required to keep the machine in proper running order, but in the wear and tear on the parts and particularly the spindles, the sleeve bearings and the driving tapes or belts; in addition, the oil will be prevented from being scattered about and damaging the material being manufactured.

Referring to the accompanying drawing, Figure 1 is a view showing my invention applied to a spinning spindle, certain parts appearing in section in a plane at right angles to the upper and lower rails supporting the spindles and substantially coincident with the axis of the spindle; Fig. 2 is a view in front elevation of a portion of the device constituting my improvement; and, Fig. 3 is a horizontal sectional view on the line x—x of Fig. 1.

In said drawing, a is the upper rail, in which is arranged the sleeve bearing b formed, as usual, with the oil cavity c; d is the lower rail carrying the step bearing e, as usual. f is the spindle journaled in said bearings carrying the whirl g.

It is the practice at present to lubricate the spindle in its upper bearing by introducing the lubricating oil from time to time into the cavity c of the sleeve bearing b. The oil

thereupon works its way through the bearing and is thrown off by the spindle so that it is not only wasted but is scattered upon other parts of the machine as well as upon the material in process of manufacture. In order to prevent this, I arrange on the spindle f directly above the whirl g in the adaptation shown, or, at least, so as to surround the lower end of the bearing b, the cup h. This cup is preferably secured on the spindle in the same manner in which the whirl g is usually secured thereon, to wit, by jamming it on the spindle, and for the purpose of forming an extended contact between the cup and the spindle, as at i, and causing the cup to rotate positively with the spindle, the cup is provided with an internal boss j.

As above stated, the cup is so arranged as to surround the lower end of the bearing b, that is, its upper edge projects above the lower end of said bearing, so that as the oil is thrown off at the lower end of the bearing by the centrifugal action of the spindle it will be caught by the cup. Inasmuch as the cup rotates with the spindle at a high rate of speed, the cup furthermore has its upper edge turned inwardly, as at k, thus imparting to the circular wall of the cup an internally channeled form, whereby to insure the confining of the oil in the cup.

I further attach to the face of the rail a the bracket portion l of a tubular conductor m whose lower end extends into the cup h and whose upper end is adapted to discharge into the cavity c. The tubular conductor m comprises a valve casing n having integral therewith the bracket portion l, a valve o in said valve casing adapted to control the flow through the latter, and the tubes p and q the former of which is screwed into the upper side of the valve casing and the latter of which is screwed into the under side of said valve casing. The tube p is bent so that its free end projects over the cavity c; the tube q is so bent as to extend down into the cup h to a point somewhat near the bottom thereof, and then off horizontally in a direction opposite to that of the rotation of the cup with the spindle. This latter portion, r, of said tube q, stands close to the circular wall of the cup and it has its free or open end beveled, as best seen in Fig. 3, whereby to insure the free entry of the oil into the tube.

In operation, the attendant merely sees that the cup is from time to time supplied with oil, being careful not to introduce so much

that when the cup is rotating at the normal speed of the spindle the oil will be thrown off from the cup. Under the rotary motion of the cup, whereby centrifugal action will 5 throw the oil against its channeled circular wall, the oil will be taken up through the tubular conductor *m* and discharged into the cavity *c*, from whence it will work its way down through the bearing *b* back into the cup; this effect continues so long as the cup is 10 rotating. The flow through the conductor *m* may be regulated by the valve *o*, as the conditions require.

My invention has the further advantage 15 that it makes it possible to keep the bearing *b* adequately supplied with oil, whatever speed the spindle may assume, by providing the bearing *b* with a vertical oil duct *s* which allows the oil to pass unimpeded down through 20 the bearing; such an oil duct has been practically impossible heretofore because it would allow the oil to pass through the bearing too quickly, although it obviously has the advantage that so long as the oil remains therein 25 the bearing is thereby freely lubricated.

The bracket *l* is detachably secured to the rail *a* by having slots *t* which receive screws *u* driven into the rail. In case the tubular conductor should become clogged by particles of 30 lint or floss taken up by the oil, it may be detached from the rail and cleaned; in furtherance of this object, the tubes *p* and *q* may be unscrewed from the valve casing *n* so as to

have free access to these parts. The amount of such lint, floss, etc. which may find its way 35 into the cup may be materially reduced by providing a cover *v* having the countersunk collar *w* carrying a set screw *x* which may bind against the bearing to hold the cover in spaced relation with but close to the cup; 40 said cover has a recess *y* to accommodate tube *q*. The cover may be raised from time to time by loosening screw *x* so as to permit access to the cup for cleaning the same.

I do not wish to be limited to any of the 45 details of construction herein set forth, what I claim being:

The combination, with a rail and an upright sleeve-bearing arranged therein, of a rotary part arranged in the sleeve-bearing, a 50 rotary cup located below said bearing, a valve casing secured detachably to the front face of the rail, a tube detachably secured to the valve casing and discharging into an elevated part of the sleeve-bearing, another 55 tube detachably secured to the valve casing and projecting downwardly into said casing, and a valve arranged in said valve casing, substantially as described.

In testimony, that I claim the foregoing, I 60 have hereunto set my hand this 12th day of September, 1907.

WILLIAM H. MCGAULEY.
